K. F. NYSTRÖM

REFRIGERATOR CAR DRIP PAN

Filed April 28, 1923

Inventor
Karl F. Nyström,
George Heidman
Attorney

UNITED STATES PATENT OFFICE.

KARL F. NYSTRÖM, OF CHICAGO, ILLINOIS.

REFRIGERATOR-CAR DRIP PAN.

Application filed April 28, 1923. Serial No. 635,404.

To all whom it may concern:

Be it known that I, KARL F. NYSTRÖM, a subject of Great Britain, and a resident of Chicago, in the county of Cook and State 5 of Illinois, have invented certain new and useful Improvements in Refrigerator-Car Drip Pans, of which the following is a description, reference being had to the accompanying drawing, which forms a part of my specification.

My invention relates to means for draining the water, resulting from the melting ice or refrigerant, from the bunkers or ice containers at the end or ends of railway 15 refrigerator cars; that is to say, the invention, more specifically stated, relates to the bottom of the bunker and the drip pan disposed throughout the bottom of the bunker whereby the water is caused to flow toward and 20 through a defined path or channel and be drained therefrom.

One object of the invention is to provide means whereby the drip pan will not only be reenforced but at the same time provide 25 a rigid and firm connection or foundation for the posts or uprights of the bulkhead of the car and also provide support for the ice holding container or basket.

Another object of the invention is to provide means whereby the water will be prevented from splashing or being thrown over the forward edge of the pan, while the car is in transit or shifted, and therefore prevented from passing through the air circu- 35 lating opening at the bottom of the bulkhead into the car proper where it is likely to damage the lading.

A further object of the invention is to provide a drip pan with an outlet or drain 40 conduit of such construction as will insure a constant draining of the water while at the same time obviating the possibility of becoming clogged by straw or other foreign matter lodging in the drain conduit.

The above enumerated objects as well as the advantages inherent in the construction 45 will all be more readily comprehended from the detailed description of the drawing, wherein:—

Figure 1 is a vertical sectional view of the lower end of an ice bunker of a refrigerator car, provided with my improved drip pan.

Figure 2 is a vertical sectional view taken

on the line 2—2 of Figure 1, looking in the 55 direction of the arrows.

Figure 3 is a sectional plan, with portions broken away, of one corner of the ice bunker and drip pan.

In order to illustrate my invention, I 60 have shown the lower part of an ice bunker usually formed at the ends of refrigerator cars as disclosed by the side and end walls 10 and 11 of the car and the bulkhead 12; the walls and bulkhead being formed in the 65 usual manner with suitable insulating material and with air circulating passages at top and bottom of the bulkhead; the bottom opening being shown at 13 in Figure 1.

In the particular exemplification of the 70 invention, where the lower end of the ice holding container is shown, the side walls consist of suitable wire mesh indicated at 14; while the bottom of the container comprises a suitable number of transversely 75 disposed members, preferably in the nature of channel beams as shown at 15, and these beams also support the ice holding racks 16, which are preferably removably secured in place by hook-bolts as at 17; the hook- 80 bolts being disposed through registering apertures in the flanges or sides of the channel beams.

The floor 18 of the bunker, namely at the end of the car, is depressed below the 85 floor 19 of the main portion of the car so as to provide a well in the floor, commensurate with the construction and of depth in keeping with the depth of my improved pan, in order that the pan may be disposed 90 below the floor level of the lading holding portion of the car.

The well in the floor is intended to receive my improved drip pan shown at 20. The pan is intended to be disposed throughout the entire well in the floor or bottom of the bunker; the pan being preferably of suitable sheet metal, with a flat bottom which rests on the floor planks of the bunker. The pan is provided with an upstanding 100 rim 21 of predetermined height, which is preferably arranged rearward of the sheathing or flashing 22 on the walls of the car so as to cause the water to flow down into the drip pan.

The bunker floor 18 is provided with a longitudinal depression, extending from side to side of the car for the purpose of receiv-

ing the channeled portion or trough 23 which is arranged preferably at the longitudinal center line of the pan. The channel or trough 23 is preferably arranged to extend throughout the length of the pan so as to cause the water to drain from opposite sides toward the trough from which it is permitted to drain by a suitable drain pipe 24.

The drain or outlet pipe 24 is preferably formed with an arcuate closed upper end 25 to prevent solid matter becoming lodged in the pipe, and the pipe for a predetermined distance at the upper end above the pan bottom is provided with a plurality of suitable perforations 26. The pipe extends upward a distance corresponding with the depth of the pan at the trough portion thereof, in order that a sufficient drain may be provided. At a point beneath the perforations 26 and beneath the pan bottom the pipe is provided with a flange or collar 27 firmly secured thereto for the purpose of supporting the drain pipe 24 in place; the flange or collar 27 being preferably disposed between the floor of the bunker and the bottom of the pan as shown.

With this construction the outlet pipe acts as a trap or strainer to prevent straw or other solids entering the outlet opening, while at the same time, because of its perforated end extending above the bottom of the pan, affording an ample drain to prevent excessive accumulation of water in the pan.

The floor 19 of the main portion of the car, at the air circulating opening 13, beneath the bulkhead 12, is provided with a splash plate 28, which consists preferably of a metallic strip or plate of suitable width removably secured to the main floor 19, so that the free longitudinal edge thereof is arranged to overlap the upper edge of the drip pan 20 along the front or bulkhead longitudinal side. The floor 19 is preferably kerfed to receive the plate 28 in order that it may extend flush with the main floor; the plate being of length to extend throughout the length of the pan and of width sufficient to overlap the forward edge of the pan to a considerable extent as shown in Figure 1.

With my improved splash plate arranged as shown and described, any water which has not drained toward the trough of the pan will be prevented from splashing over the top of the pan and onto the floor of the car where it would be likely to flow into the car proper and damage the merchandise with which the car is laden, as, however, has been the case in refrigerator cars as heretofore constructed, wherein the water from the drip pan has been caused to splash over the forward edge of the pan, during the jarring and lurching of the car, causing serious

damage to the merchandise. This difficulty, however, has been obviated with my improvement, both by reason of a drip pan with a central trough and the employment of a splash plate as shown and described.

The drip pan is provided with metallic blocks or shoes 29, 30, which are arranged with the lower ends of the shoes preferably located within and riveted or rigidly secured to the drip pan and disposed upwardly to support the ice holding container or basket. The blocks or shoes 29 are arranged in the corners of the drip pan at what may be termed the rear side, namely adjacent to the end wall of the car, and therefore reinforce the upstanding flanges or sides of the pan; while the blocks or shoes 30, at the forward or bulkhead side of the pan, due to the splash plate 28, and the fact that the drip pan extends slightly beneath the bulkhead, are arranged at a slight distance from the forward side or flange of the pan, as shown in Figure 1.

The blocks or shoes are preferably formed with a slight off-set or recess 31 at the lower ends in order that the major portion of the shoes above the pan sides may extend flush with the side and end walls of the bunker and therefore permit the upstanding sides of the pan to be disposed between the blocks or shoes and the walls of the bunker and at the same time permit the thin sheet or flashing 20 to also overlap the upstanding sides or flanges of the drip pan as shown at the left in Figure 1.

The blocks or shoes are adapted to be secured to the bottom members of the ice holding container or basket and also provide rigid connection with the posts of the bulkhead at the front of the bunker, with the result that a very firm, non-shiftable construction is provided adapted to withstand the severe jars and shocks to which the car is likely to be subjected; and the riveting of the shoes to the pan will form a very rigid foundation for the posts.

The bottom of the drain pipe 24 is shown provided with a cup member 32, suitably secured thereto, to provide a water seal and thus prevent the inflow of air through the conduit. With the water seal arranged beneath the floor, namely on the car exterior, the cup member 32 is not only easily accessible, but cleaning of the member may be done without entering the car.

With the depressed floor and construction of drip pan as shown and described, it is apparent that the air circulating passage beneath the bulkhead is unobstructed and the chilled air allowed to circulate along the bottom of the main portion of the car and therefore permitted to freely pass beneath the lading holding floor-rack, a portion whereof is shown at 33.

I have shown what I believe to be a sim-

ple embodiment of my invention, which has been described in terms employed merely as terms of description and not as terms of limitation, as structural modifications are possible and may be made without, however, departing from the spirit of my invention.

What I claim is:—

1. In a refrigerator car bunker, a drip pan arranged throughout the bottom of the bunker, provided with upstanding sides and a central portion of greater depth than the major portion of the pan, a take-off conduit arranged in said portion, extending upwardly a distance equal to the depth of the pan and provided with perforations, and reinforcing blocks or shoes secured to the pan adjacent to the corners thereof and offset to overlap the sides of the pan, the upper ends of said blocks or shoes being adapted to be secured to and to support the ice holding container.

2. In a refrigerator car ice bunker, a drip pan provided with upwardly disposed sides and a depressed portion or trough, a drain conduit, the upper end whereof is located in said trough portion of the pan, blocks or shoes located in the pan adjacent to the corners thereof and recessed at the lower ends to receive the sides of the pan, while the upper ends of said shoes are adapted to support an ice holding container, and a sheathing or flashing secured to the walls of the bunker and arranged in lapping relation with the pan sides.

3. In a refrigerator car ice bunker having a depressed floor, a drip pan disposed throughout the bottom of the bunker and provided with vertical sides, the floor and pan being provided with corresponding

channels extending transversely of the car to provide a water-receiving trough, a drain conduit having an upper perforated end arranged in said trough to extend upwardly a distance corresponding substantially to the depth of the pan, a lining or flashing arranged on the walls of the bunker in lapping relation with the sides of the pan, reinforcing blocks or shoes adapted to be secured to the pan bottom and recessed at the lower ends to receive the flashing and sides of the pan, the shoes being adapted to extend upwardly adjacent to the walls of the bunker and to support the ice holding container of the bunker, and a splash-plate adapted to be disposed transversely of the forward longitudinal side of the pan.

4. In a refrigerator car bunker, the floor whereof is depressed below the main floor of the car and provided with a channel extending from side to side of the car, a drip-pan extending throughout the bottom of the bunker and of depth substantially equal to the depth of the floor depression, the pan being provided with a longitudinal trough disposed in said channel and substantially equal to the length and width thereof, a drain conduit arranged in the trough of the pan and extending upwardly a distance equal to the depth of the pan and provided with an upper closed end, and a splash plate removably secured to the main floor of the car in lapping relation with the forward or bulkhead side of the pan.

KARL F. NYSTRÖM.
